18 Claims. (Cl. 89—1.7)

1

This invention relates to apparatus for launching projectiles and is illustrated herein as embodied in a rocket launching apparatus adapted for use in combat airplanes. It is to be understood, however, that, in some of its aspects, the invention is not limited to rocket launching apparatus and that, with certain modifications, the apparatus may be adapted for use on carriers other than airplanes.

The increasing use, in recent years, of rockets launched from combat airplanes has necessitated the development of launching devices for carrying and firing the rockets. One type of device heretofore used for launching rockets from airplanes consisted of a plurality of rocket carrying tubes mounted under the wings of an airplane, the tubes being arranged to be dropped from the airplane after the completion of a mission. Each tube was provided with a pair of electric contacts placed against the tail rings on the rocket, in position to set off an electric igniter in the rocket, which in turn ignites the propelling charge, upon operation by the pilot of a firing trigger located on the joy stick of the airplane. The number of rockets that can be launched from any one airplane in this manner is necessarily limited, since any appreciable increase in the weight of the launchers would increase the air resistance, with a resultant decrease in the speed of the airplane. Moreover, the rocket carrying tubes being mounted outside the airplane, the length of each tube must similarly be limited, and this has an important effect on the accuracy with which the rockets can be directed at a target, since the longer the tube through which a rocket is fired, the more the rocket is likely to maintain a true course in its flight.

It is an object of the present invention to provide a rocket launching apparatus by the use of which a larger number of rockets may be launched from airplanes than has heretofore been possible, and which can be readily installed in an airplane without necessitating substantial alterations in the airplane structure and removed therefrom when it is desired to utilize the airplane for launching other types of projectiles, or for other purposes.

It is another object of the invention to provide a rocket launching apparatus adapted to move a plurality of rockets one at a time from within the airplane into a launching position outside the airplane, to fire each rocket after the same has been moved into launching position, and to dispose of defective or misfired rockets.

It is a further object of the invention to pro-

2

vide a rocket launching apparatus by the use of which a plurality of rockets may be indexed and fired at a rapid rate, and in which the indexing and firing of the rockets, as well as the release of undischarged rockets, are remotely controlled by the airplane pilot.

With these and other objects in view, the illustrated rocket launching apparatus comprises, in accordance with a feature of the invention, 10 a magazine adapted to hold a plurality of rockets, the magazine being mounted in the bomb bay of an airplane in such manner that a portion of the magazine projects through an opening in the airplane and is connected to a long projection 15 tube that is supported on the underside of the fuselage and through which the rockets carried by the magazine are launched successively. In accordance with another feature of the invention, means is provided whereby the magazine 20 and the projection tube may be adjusted as a unit to obtain the desired angle of elevation for the launching of the rockets.

The rockets are carried in the magazine by a plurality of tubes that are connected by links to 25 form an endless chain and moved intermittently by an indexing mechanism constructed and arranged to move one rocket carrying tube at a time into launching position in register with the previously mentioned projection tube. Preferably, the indexing mechanism is operated by 30 remotely controlled power means, auxiliary means being also provided for manual operation of the indexing mechanism in the event of failure of the power means. The operation of the indexing 35 mechanism is controlled by a clutch and brake mechanism and, in accordance with a feature of the invention, clutch control means is provided which is operative at predetermined times in the power or manual operation of the indexing 40 mechanism automatically to disengage the clutch and apply the brake after the indexing mechanism has moved the rocket carrying tube chain a distance substantially equal to the spacing between the centers of two adjacent tubes.

45 Each rocket in a rocket carrying tube which has been moved into rocket launching position is held in that position until fired and, in accordance with a further feature of the invention, means is provided for preventing the indexing of the rocket carrying tube chain while a rocket is in launching position. As herein illustrated, the rocket is held in its launching position by a retaining lever arranged to engage the flange on the rear end of the rocket. This retaining lever is connected, by means including

a spring, to a microswitch that is connected in the electrical circuit controlling the indexing mechanism. The spring normally maintains the microswitch closed and holds the previously mentioned retaining lever in position to be engaged by the flange of a rocket contained in a tube which has been moved into rocket launching position by the indexing mechanism. Engagement of the rocket flange with the retaining lever causes the lever to swing in a direction to open the microswitch, thereby preventing initiation of the power operation of the indexing mechanism until the rocket has been launched, whereupon the spring acts to again close the microswitch and to move the retaining lever into position to engage the flange of the next succeeding rocket.

Another feature of the invention relates to a firing mechanism under the control of the airplane pilot and adapted to fire the rockets successively at the end of each indexing operation. In the illustrated apparatus, the firing mechanism includes a pair of insulated and individually yieldable contact fingers adapted to engage the contact members on the rear end of the rocket to set off an igniter in the rocket, which in turn ignites the propelling charge.

To insure that the firing mechanism will not be rendered operative to fire a rocket unless the rocket is correctly positioned in alignment with the projection tube, there is provided, in accordance with a further feature of the invention, means associated with the firing mechanism and with the indexing mechanism and operative to prevent the operation of the firing mechanism until the indexing mechanism has completed its operation to move a rocket carrying tube into rocket launching position. In the illustrated construction, the means just mentioned comprises a microswitch mounted on the magazine and connected in the electrical circuit controlling the firing mechanism. Upon initiation of the power operation of the indexing mechanism, the microswitch, which is normally closed, is opened by engagement thereof with the periphery of a cam carried by the indexing mechanism and remains open until the indexing mechanism has completed its indexing movement. The firing mechanism is further provided with manual locking means for rendering the firing mechanism inoperative at all times when the apparatus is not in operation, to prevent accidental firing of a rocket.

For releasing any misfired or defective rocket so that it may be ejected from the magazine, there is provided, in accordance with another feature of the invention, a release mechanism controlled by a switch on the instrument panel. As herein illustrated, the release mechanism comprises a solenoid operatively connected to the previously mentioned rocket retaining lever, the arrangement being such that, when the pilot operates the release switch to release an undischarged rocket, the solenoid is energized and actuates the retaining lever to release the rocket, which is then free to be ejected through the rear end of the magazine by a blast of air passing through the projection tube.

These and other features of the invention will now be described in detail with reference to the accompanying drawings, and pointed out in the claims.

In the drawings,

Fig. 1 is a view in side elevation of the forward end of an airplane, illustrating the apparatus embodying the invention mounted partly

in the bomb bay of the airplane and partly outside the airplane;

Fig. 2 is a vertical section along the line II-II of Fig. 1, illustrating the manner in which the forward portion of a projection tube, shown in that figure, is attached to the airplane;

Fig. 11 is a detail sectional view taken along the line XI-XI of Fig. 10;

Fig. 12 is a view in side elevation and on an enlarged scale, taken in the direction of the arrow in Fig. 5, of the firing mechanism in inoperative position and of retaining means located at the launching end of the apparatus for locking each rocket in its launching position;

Fig. 13 is a view substantially similar to Fig. 12 but illustrating the firing mechanism in operative position;

Fig. 14 is a bottom view, on a reduced scale, of the firing mechanism taken in the direction of the arrow in Fig. 12;

Fig. 15 is a sectional view of a portion of the firing mechanism taken along the line XV-XV of Fig. 13;

Fig. 16 is a detail view of locking means for rendering the firing mechanism inoperative;

Fig. 17 is a vertical section, on an enlarged scale, taken along the line XVII-XVII of Fig. 12;

Fig. 18 is a transverse section along the line XVIII-XVIII of Fig. 17, this view showing more particularly the means for locking each rocket in launching position; and

Fig. 19 is mainly a wiring diagram.

The illustrated apparatus is a rocket launching apparatus adapted to be used in combat airplanes. In the embodiment shown herein by way of example, the apparatus is mounted in the forward bomb bay of a bombing

airplane A (Fig. 1), with the upper portion of the apparatus supported in the bomb bay and the lower portion projecting through an opening in the airplane. The apparatus may be installed in the bomb bay of an airplane from which the bombs have been temporarily removed, without altering the airplane structure, and easily and quickly removed therefrom in order to reconvert the airplane to its normal use. It is to be understood, however, that, with certain slight modifications, the apparatus may be adapted for use in craft other than airplanes.

The apparatus consists principally of a magazine M (Fig. 1) adapted to hold a plurality of rocket carrying tubes; an indexing mechanism I for moving the tubes successively into rocket launching position; a firing mechanism F for firing the rockets successively; and a release mechanism for causing defective or unfired rockets to be ejected from the airplane. The indexing, firing and release mechanisms are all controlled by the airplane pilot by means of switches located on the instrument panel.

The magazine

Referring to Figs. 1 and 6, the magazine M comprises a frame consisting of two end plates 20, 22 joined by rods 24. The magazine is removably mounted in the bomb bay of the airplane A and is attached thereto at its upper end by means of a hanger comprising a laterally extending hollow shaft 26 formed with flanged bosses 28 riveted to angle brackets 30, which are bolted to the upper end portions of the end plates 20, 22, and two inclined rods 32 pivotally connected at their lower ends to the bosses 28 and at their upper ends to a connecting member 34. The connecting member is provided with a socket 36 for the reception of a downwardly extending threaded rod 38 pivotally connected at its upper end to a lug 40 depending from a cross-head 42 that is secured to brackets 44 provided in the bomb bay. Mounted on the lower end of the rod 38 is a hand wheel 46 by means of which the apparatus may be raised or lowered in the bomb bay, the hand wheel being provided with an internally threaded hub 47 and a thrust bearing 48 which engages the connecting member 34. Intermediate its upper and lower ends the magazine is provided with brackets 50 (Fig. 5) which extend between the opposite end plates at the front and rear of the magazine and by means of which the magazine may be mounted on bomb rails 52 in the bomb bay in any desired angular position relative to the longitudinal axis of the airplane. The brackets 50 are provided with bolts 54 extending through inclined slots 56 provided in plates 58 which are suspended on hooks 60 on the bomb rails 52 and secured thereto by bolts 61.

The magazine M is designed to hold a plurality of rocket carrying tubes 62 which are connected together in an endless chain by links 64 mounted on the opposite ends of the tubes. The magazine of the illustrated apparatus is adapted to carry sixteen tubes, although this number may be increased to the maximum permitted by considerations of weight and of the space in which the magazine is to be mounted. The tubes 62 are moved in a closed, non-circular path in guideways formed by angle irons 66 (Figs. 10, 11 and 17), and guide plates 68 secured to the inner surfaces of the end plates 20 and 22. The guide plates 68 are preferably made in two sections, as shown in Fig. 17, the lower portions of the plates 75

being secured to the end plates 20, 22 by bolts 70 engaging in elongated slots 72, by means of which the lower portions of the guide plates may be adjusted heightwise relatively to the upper portions thereof to compensate for any slack which may be present in the chain of rocket carrying tubes. Between the guide plates 68 on the opposite end plates extend flanged reinforcing tubes 74 bolted to the guide plates.

- 10 The lower end portion of the rear end plate 20 is provided with a circular opening having an internal diameter substantially equal to the internal diameter of a rocket carrying tube 62, and has secured thereto a flanged collar 76 (Fig. 1) through which the rockets are inserted into the rocket carrying tubes during the loading of the magazine, and through which misfired rockets are ejected in a manner explained hereinafter. The lower end portion of the front end plate 22 15 is provided with a similar circular opening and has secured thereto a flanged collar 78, to which is attached a projection tube 80, through which the rockets are launched one at a time. The tube 80 extends from the bomb bay to the nose 20 of the airplane, the length of the tube being such as to afford the maximum opportunity for the rockets to maintain a true course in flight. The projection tube 80 is surrounded by straps 82 to which are riveted brackets 84, 86 and 88 25 (Figs. 2, 3 and 4). Pivotally connected to the brackets 84 and 88 are rods 90, which are also pivotally connected at 91 to a bracket 92 depending from the airplane fuselage. The forward portion of the tube 80 is supported by a bracket 30 94 depending from the airplane fuselage and connected by a pivot pin 96 to the bracket 84. The intermediate portion of the tube 80 is connected to the airplane by turnbuckles 98 (Fig. 3) 35 pivotally connected by the pin 91 to the bracket 92 and by a pin 100 to the bracket 86. The rear portion of the tube 80 is connected to the airplane by turnbuckles 102 the lower ends of which are pivoted at 104 to the bracket 88 (Fig. 4) and the upper ends of which are pivoted at 106 to a bracket 108 depending from the airplane fuselage. 40 The apparatus and the projection tube may be adjusted as a unit heightwise of the airplane to obtain the desired angle of elevation of the projection tube for the launching of the rockets. 45 The pivotal connections just described provide for limited endwise movement of the projection tube during this adjustment, the tube being secured in its adjusted position by adjustment of the turnbuckles 98 and 102.

The indexing mechanism

The indexing mechanism I is mounted on the upper end of the rear end plate 20 of the magazine (Figs. 1, 5 and 6) and is arranged to move the rocket carrying tubes 62 successively into rocket launching position in register with the projection tube 80. The tubes 62 are supported and moved one at a time by sprockets 110 (Figs. 6 and 9) mounted on the opposite ends of a shaft 66 112 mounted in bearings 114 in the upper end portions of the end plates 20, 22. The shaft 112 is driven from a primary source of power through a reduction gearing, comprising a gear 116 mounted on the shaft 112 and meshing with a pinion 118 keyed to one end of a shaft 120 the other end of which is journaled in a bearing in a shaft 122 mounted in a bearing 124 in a housing 126 mounted on the upper end of the rear end plate 20. The shaft 122 operates a varying speed drive mechanism substantially similar to

that described in United States Letters Patent No. 2,309,595, granted on January 26, 1943, upon an application of Lester E. James, to drive the sprocket shaft 112 at a low velocity at the beginning and end of each indexing cycle and at a high velocity in the intermediate portion of the cycle so that the rocket carrying tube chain will be rotated smoothly. This varying speed drive mechanism includes a sun gear 128 (Fig. 9) mounted on the outer end of the previously mentioned shaft 120 and meshing with planetary gears 130, which also mesh with the internal teeth 132 of a ring gear 134 mounted on the inner end of the shaft 122. The planetary gears 130 are mounted on shafts 136 journaled in a spider cage 138 (Fig. 6) connected, by an oscillating arm 140 (Figs. 6 and 9) mounted on one of the shafts 136, to the inner end of an eccentric shaft 142. A pinion 144, keyed to the outer end of the eccentric shaft 142, meshes with the external teeth 146 of the ring gear 134. The outer end of the shaft 122 carries a worm gear 148 which meshes with a worm 150 (Figs. 5 and 9) fast on a sleeve 151 rotatably mounted on a vertical drive shaft 152 journaled in the housing 126. The upper end of the shaft 152 carries a worm gear 154 which meshes with a worm 156 fast on a shaft 158 connected to the shaft of an electric motor 160 secured to a housing 162 mounted on top of the housing 126. The drive shaft 152 rotates continuously while the motor is running and the worm sleeve 151 is brought into driving engagement with the drive shaft to operate the indexing mechanism by engagement of a multiple disk friction clutch 164 of the type described in United States Letters Patent No. 2,201,676, granted on May 21, 1940, upon an application of Allen R. Coe. The clutch, which is interposed between the lower end portion of the sleeve 151 and the shaft 152, is actuated by a forked clutch shifting lever 166 fulcrumed at 168 on the housing 126. The upper ends of the arms of the lever 166 carry blocks 170 which engage in an annular groove 171 provided in a clutch sleeve 172 slidably mounted on the lower end of the shaft 152. The upper end of the clutch shifting lever 166 carries an eyebolt 174 (Fig. 5) to which is anchored one end of a spring 176, the other end of which is secured to a cover plate 178 on the housing 126. Mounted on the lower end of the sleeve 151 is a brake disk 180 with which cooperates a brake shoe 182 mounted on an eccentric shaft 184 (Fig. 8) journaled in ears 186 on the housing 126. A lever 188 clamped on the shaft 184 is connected by a pin 190 to a link 192 pivotally connected to a pin 194 integral with the clutch shifting lever 166.

For actuating the lever 166 to release the brake 182 and engage the clutch 164 there is provided means including a clutch tripping bell-crank lever 196 (Fig. 5) fulcrumed at 198 on the housing 126. The horizontal arm 200 of the bell crank 196 is connected to the plunger 202 of a solenoid 204 that is secured by a clamp 206 to a bracket 208 mounted on the outer surface of the rear end plate 20. The bell crank 196 has an upwardly extending arm 210, to the upper end of which is pivotally connected a forked latch lever 212 arranged to engage the hooked tail 214 of a latch 216 pivotally connected at 218 to the lever 166. The lever 212 is biased by a spring 220 connected at one end to the lever 212 and at its opposite end to an eye in the arm 210. The latch 216 is biased by a spring 222 attached at one end to the latch and at its opposite end to a lug 224 on the lever 166.

Referring to Fig. 5, in which the parts are shown in inoperative position, the indexing mechanism operates as follows to move a rocket carrying tube 62 into rocket launching position in register with the projection tube 80. The power being turned on to start the motor and the solenoid switch being closed, when the indexing switch is operated a circuit is established through a lower relay coil 225 (Fig. 19) to energize the solenoid 204, thus: From the positive side of the source of power to the closed solenoid switch, and through this switch to the closed indexing switch, thence to a normally closed microswitch 268, the purpose of which will be explained hereinafter, thence to the relay coil 225, and from the relay coil to ground. Current passing through the relay coil causes the relay contacts to be closed, establishing a circuit from the positive side of the source of power through the closed solenoid switch to the relay, thence to the solenoid 204, and thence to ground, whereupon the solenoid 204 is energized and the solenoid plunger 202 moved downward, causing the clutch tripping lever 196 to swing in a counterclockwise direction and the latch lever 212 to engage the hooked tail 214 of the latch 216. During the continued counterclockwise movement of the lever 196, the latch lever 212 pulls the latch 216 toward the left of Fig. 5, against the tension of the spring 220, and causes the clutch shifting lever 166 to swing in a counterclockwise direction against the tension of the spring 176. As a result of this swinging movement of the lever 166, the brake shoe 182 is disengaged from the brake disk 180 and the clutch sleeve 172 moved upward to engage the clutch 164 and bring the worm sleeve 151 into driving engagement with the drive shaft 152 to operate the indexing shaft 122. The shaft 122 rotates in the direction of the arrow in Fig. 5 and, through the gear train illustrated in Figs. 6 and 9, operates the sprocket shaft 112 to move one rocket carrying tube into rocket launching position.

To insure that the clutch 164 will be held firmly engaged during an indexing cycle and also that the clutch will be disengaged and the brake applied upon completion of the indexing cycle, there is provided a clutch control mechanism comprising a pair of cam disks 226, 228 (Figs. 5 and 6) mounted on the outer end of the shaft 122 and bolted together for rotation in unison therewith. The cam disk 226 is provided with three notches 230, within which a roller 232 carried by the clutch shifting lever 166 is arranged to engage successively upon completion of each indexing cycle. Upon initiation of an indexing cycle by operation of the indexing switch, as previously explained, the clutch shifting lever 166 swings in a counterclockwise direction, as seen in Fig. 5, and the roller 232 is withdrawn from engagement with a notch 230 in the cam disk 226. During rotation of the shaft 122, the roller rides on the periphery of the cam disk between two notches and holds the clutch firmly engaged until the roller engages in the next notch 230, whereupon the spring 176 causes the lever to swing in a clockwise direction to disengage the clutch and apply the brake 182. The notches 230 in the cam disk 226 are spaced equal distances from one another, the arrangement being such that the clutch will be disengaged and the brake applied to bring the indexing shaft 122 to rest after rotating through a distance corresponding to the spacing between the centers of two adjacent tubes 62 of the rocket carrying tube chain, that is, through

a distance sufficient to move one tube into rocket launching position in register with the projection tube 80.

The cam disk 228 is provided on its periphery with three depressions which are spaced equal distances from one another and with which the latch 216 successively engages at the end of each indexing cycle. Shortly after the initiation of the rotation of the indexing shaft 122, that is to say, after the latch lever 212 has acted to pull the latch 216 toward the left of Fig. 5 to cause the clutch shifting lever 166 to swing in a counter-clockwise direction to engage the clutch, the latch is caused, by engagement with the part of the periphery of the cam 228 between two depressions, to swing in a clockwise direction against the tension of the spring 222. As a result of this movement of the latch, its hooked tail 214 is moved out of engagement with the latch lever 212 and is held disengaged by continued engagement of the latch with the above-mentioned part of the periphery of the cam 228 until the end of an indexing cycle, so that the clutch shifting lever 166 will thereafter be free, upon engagement of the roller 232 with a notch 230 in the cam 226, to swing in a clockwise direction to disengage the clutch and apply the brake. Upon stopping of the rotation of the shaft 122, the latch 216 engages the next depression of the cam 228, where it is in position to be actuated by the clutch tripping lever 196 upon the next operation of the indexing switch by the pilot to move another rocket carrying tube into rocket launching position.

The indexing mechanism just described may be operated manually if for any reason the power means cannot be utilized. For this purpose a hand crank 234 may be secured to the lower end of the shaft 152, as shown in Fig. 5, and a cable 236 attached to the arm 200 of the clutch tripping lever 196 for actuating the lever to cause release of the brake and engagement of the clutch. After engagement of the clutch, rotation of the shaft 152 by means of the hand crank 234 will operate the indexing mechanism in the same manner as when the mechanism is power operated, and the previously described clutch control mechanism will be effective to control the rotation of the shaft 122 to cause it to come to rest at the end of an indexing cycle.

The manual means just described may also be used, in the absence of power, for indexing the rocket carrying tube chain during the loading of the magazine, which takes place before the apparatus is installed in the airplane. The loading operation may be effected either by means of the power-operated indexing mechanism or by means of the hand crank 234. Regardless, however, of the means by which the operation is effected, the cable 236 is used in place of the indexing switch, which is located in the cockpit of the airplane, to actuate the clutch tripping lever 196 to cause engagement of the clutch. If the loading is done by power, the motor switch is closed and the solenoid switch (see Fig. 19) left open. With the motor running, a rocket R (Fig. 18) is inserted through the collar 76 (Fig. 1) into the lowermost tube 62 in the magazine, the rocket being inserted with the nose forward and the fins 238 (Fig. 18) folded. The cable 236 (Fig. 5) is next pulled downward to actuate the clutch tripping lever 196 to release the brake 182 and engage the clutch 164. The indexing mechanism will thereupon be operated to index the tube chain so that the filled tube will be moved up and an empty

tube will be moved down into position to receive a rocket. This procedure is repeated until all the tubes have been filled. The same procedure is employed to load the magazine manually, when the electric motor cannot be used, the hand crank 234 being secured to the shaft 152 and used to rotate the shaft after each successive engagement of the clutch by a pull on the cable 236.

Each rocket R in the tube 62 which has been moved into rocket launching position in register with the projection tube 80 is held, until fired by mechanism to be described hereinafter, by a retaining lever 240 (Figs. 5, 12, 17, 18 and 19) pivoted at 242 on a bracket 244 mounted on the lower end of the rear end plate 20. The upper end of the lever 240 extends through a slot in the collar 76 and is provided with a slot 246 (Fig. 18) which is engaged by the flange 248 on the rear end of the rocket. As shown in Fig. 18, each rocket carrying tube 62 is cut away at 250 to provide clearance for the lever 240. The upper end of the lever 240 is bifurcated and has pivotally connected thereto at 252 an arm 254 having a cam portion 255 adapted to bear against the collar 76. When a rocket is fired, the blast of the propelling charge causes the arm 254 to swing in a clockwise direction, as seen in Fig. 18, and the cam 255 to act against the collar 76, so as to cause the lever 240 to swing in a direction to release the rocket flange from engagement with the slot 246. Upon emergence of the rocket from the projection tube 80, the rocket fins 238 open to stabilize the rocket in flight.

Mechanism is provided, in accordance with the invention, for preventing initiation of the power operation of the indexing mechanism while a rocket is in launching position. As shown in Figs. 5 and 19, the retaining lever 240 is provided with an upwardly extending arm 256 which is connected by a rod 258 to a bell crank 260 pivotally connected to a downwardly extending lug 262 of a housing 264 supported by a bracket 266 secured to the bracket 244. The bell crank 260 is adapted to operate the previously mentioned microswitch 268 in the housing 264, this microswitch, as already stated, being included in circuit with the coil of the relay 225 which controls the indexing solenoid 204 (see wiring diagram, Fig. 19). The rod 258 carries a spring 269 confined between a shoulder provided on the right-hand end of the rod 258 and the bracket 266 through which the rod extends. The spring 269 normally maintains the microswitch 268 closed and holds the retaining lever 240 in position to be engaged by the rocket flange 248. When the flange of a rocket R engages in the slot 246 in the retaining lever 240, the lever is caused to swing in a clockwise direction, as seen in Fig. 5, thus causing the rod 258 to be moved to the right to open the microswitch 268 and to compress the spring 269. With the microswitch open, operation of the indexing mechanism will be prevented until the rocket has been discharged, whereupon the spring 269 under compression will expand, thereby closing the microswitch and returning the lever 240 to its rocket engaging position.

The firing mechanism

The firing mechanism F (Figs. 1 and 5) is mounted on the lower end portion of the rear end plate 20 directly above the collar 76, and is actuated by a solenoid 270 (Figs. 5, 12, 13 and 19) energized by operation of a firing switch located on the control panel in the cockpit of the airplane. The solenoid is secured by means of a

clamp collar 272 to a casting 274 mounted on the end plate 20. The plunger 278 of the solenoid 270 is connected by a clevis 276 to a link 280 pivotally connected at 282 to a two-arm lever 284 fulcrumed at 286 to the casting 274. The lever 284 has a bifurcated portion 288 to which is pivotally connected at 289 a downwardly extending latch 290 biased by a spring 292 attached at one end to the upper end of the latch and at its opposite end to the link 280. The lower hooked end 294 of the latch 290 is arranged to engage a shoulder 296 on a rack slide 298 mounted for vertical reciprocating movement in the casting 274. The slide 298 moves upward against the resistance of a compression spring 300 mounted in a bore in the slide and confined between the slide and a stationary abutment 302 on the casting 274. The teeth 304 of the rack slide mesh with a gear segment 306 formed integral with a block 308 of non-conducting material mounted on a shaft 310 rotatably mounted in the casting 274. The block 308 is provided with grooves for the reception of a pair of contact fingers 312 mounted on studs 314 carried by the block 308, the fingers being arranged, upon operation of the firing switch, to swing in a clockwise direction, as seen in Fig. 13, to engage contact members 348 and 350 on the rear end of the rocket, through slots provided in the collar 76. Engagement of the tips of the fingers 312 with the contact members on the rocket sets off an igniter in the rocket, which in turn ignites the propelling charge in the rocket. The fingers 312 are backed by spring-pressed plungers 316 mounted in the block 308 to permit the fingers to yield individually when engaging the contact members on the rocket. Immediately after engaging the contact members on the rocket, the fingers are caused to swing reversely, to return to inoperative position, and are held in that position until the next actuation of the firing switch by the pilot, thereby insuring against possible damage to the fingers resulting from blast produced by a discharged rocket. For this purpose the fingers 312 are provided with notches 318 which, upon return of the fingers to their inoperative positions, are arranged to be engaged by a crossbar 320 of a substantially T-shaped latch 322 to lock the fingers against clockwise movement until actuated by operation of the firing switch. The latch 322 is pivotally mounted on a pin 323 mounted in lugs 324 on a plate 326 fixed by screws 328 to the casting 274 and insulated therefrom by a plurality of layers 330 of material such as leather which lessen the shock when the fingers 312 strike against the plate 326 upon their return to inoperative position. The latch 322 is actuated against the resistance of a spring 332 that surrounds the pin 323 and bears against the inner face of the latch. In the inoperative position of the firing mechanism the upper end of the latch 322 is engaged in a notch formed in the heel portion 334 of a detent 336 pivotally connected at 338 to the lever 284, the detent having connected thereto one end of a spring 340 the other end of which is connected to the lever 284.

Fig. 12 shows the firing mechanism in inoperative position. When the pilot operates the firing switch to fire a rocket which has been moved into launching position, a circuit is established through the closed solenoid switch (see wiring diagram, Fig. 19), the indexing switch, a release switch, a normally closed microswitch 376, and the coil of a relay 341, causing the relay contacts to be closed to establish an energizing cir-

cuit from the closed solenoid switch through the relay and the firing solenoid 270 to ground, as a result of which the solenoid 270 is energized and causes the lever 284 to swing in a clockwise direction as seen in Fig. 13. Clockwise movement of the lever 284 causes the heel portion 334 of the detent 336 to depress the upper end of the latch 322, against the resistance of the spring 332, thereby moving the crossbar 320 of the latch out of the path of the fingers 312, which are thereafter free to be moved into operative position, the detent 336 continuing to swing in a clockwise direction until stopped by engagement with a stop pin 342 on the casting 274. Upon being depressed by the detent 336, the upper end of the latch 322 is moved out of engagement with the notch in the heel portion 334 of the detent, and thereafter moves along the lower edge face of the heel portion, pushing this portion of the detent upward against the tension of the spring 340, into the position shown in Fig. 13. When the firing solenoid 270 is deenergized and the lever 284 swings in a counterclockwise direction, the detent swings in the same direction, under the action of the spring 340, to return to its normal position, shown in Fig. 12, in which the upper end of the latch is again engaged in the notch in the heel portion of the detent. In this position the latch 322 locks the contact fingers against clockwise movement until released by the detent upon a succeeding energization of the firing solenoid. Clockwise movement of the lever 284 simultaneously causes the latch 290 to move upward until its hooked portion 294 engages the shoulder 296 on the rack slide 298, and pulls the slide upward, compressing the spring 300, the extent of upward movement of the slide being variably determined by the engagement of a lug 344 on the latch 290 with an adjustable stop screw 346 mounted on the casting 274. Upward movement of the rack slide 298 causes the block 308, which is integral with the gear segment 306, to be rotated in a clockwise direction, as seen in Fig. 13, to move the fingers 312 into engagement with the contact members 348 and 350 on the tail of the rocket R (see Fig. 5). The engagement of the fingers 312 with the contact members 348 and 350 on the rocket is timed to coincide substantially with the engagement of the lug 344 of the latch 290 with the stop screw 346. Engagement of the lug 344 with the screw 346 causes the latch 290 to swing, against the action of the spring 292, in a direction to cause the hooked end 294 of the latch to be disengaged from the shoulder 296 of the slide 298, which is thereupon moved downward by the spring 300 under compression, so that the gear segment 306 and the block 308 will be rotated in a counterclockwise direction, as seen in Fig. 13, to return the fingers 312 to their inoperative positions. As previously explained, the fingers, upon their return to inoperative position, are locked in that position by engagement of the crossbar 320 of the latch 322 with the notches 318 of the fingers, thereby insuring against movement of the fingers until actuated by the next operation of the firing switch.

Near the end of their movement into operative position the fingers 312 are energized, to ignite the secondary charge in the rocket, by engagement of the convex outer ends of the studs 314 (see Fig. 15) with contact pins 352 on the lower ends of conductors 354 in the form of leaf springs secured by screws 356 to plates 358 of a non-conducting material secured by screws 360 (Figs. 12 and 14) to the casting 274. The electric current

for energizing the fingers 312 is supplied from a suitable source of power through wires 362 attached to the screws 356.

For preventing accidental firing of a rocket at all times when the apparatus is not in use, there is provided a manually controlled firing mechanism locking means. Referring to Figs. 5, 14 and 16, the locking means comprises a spring-pressed plunger 364 provided with a knurled knob 366 and mounted in a socket 368 formed integral with the casting 274. The plunger 364 is provided with two diametrically opposed fins 370 which are arranged to engage in either of two pairs of diametrically opposed notches 372, 374 provided in the socket 368, the notches 372 being of greater depth than the notches 374. When the fins 370 on the plunger 364 engage in the notches 372, the inner end of the plunger projects beyond the end of the socket 368 into the path of movement of the detent 336, thereby preventing the detent from being moved sufficiently to release the latch 322, and hence preventing the operation of the firing mechanism.

For preventing operation of the firing mechanism until a rocket is in correct launching position in register with the projection tube 80, there is provided the previously mentioned microswitch 376 (Fig. 5) mounted on the cover plate 178 of the housing 126 and included in circuit with the relay 341 which controls the firing solenoid 270 (see wiring diagram, Fig. 19). The microswitch 376 is normally closed while the indexing mechanism is in inoperative position, being in register with a notch 230 in the cam disk 226. However, while the indexing mechanism is operated, engagement of the periphery of the cam disk 226 with the microswitch 376 opens the switch and prevents actuation of the firing mechanism by operation of the firing switch.

The release mechanism

For releasing an undischarged or defective rocket so that it may be ejected from the magazine in a direction away from the projection tube 80, there is provided a release mechanism including a rod 378 (Figs. 5 and 19) connected at its lower end to the lower end of the retaining lever 240. The upper end of the rod 378 is connected by a link 380 to the plunger 381 of a solenoid 382 secured by a clamp 384 to the lower end portion of the rear end plate 20. When it is desired to eject an undischarged or defective rocket from its carrying tube which has been moved into rocket launching position, the pilot operates a release switch located on the control panel in the cockpit of the airplane. This establishes a circuit from the positive side of the source of current, through the closed solenoid switch (Fig. 19), the indexing switch, and the coil of a relay 383 to ground, causing the relay contacts to be closed to establish an energizing circuit for the solenoid 382, from the closed solenoid switch through the relay 383 and the release solenoid 382 to ground. Thereupon the solenoid 382 is energized, causing the rod 378 to be moved upward and the retaining lever 240 to swing in a counterclockwise direction, as seen in Figs. 5 and 19, to release the rocket flange 248 from engagement with the slot 246 in the retaining lever. As the lever 240 thus swings in a counterclockwise direction, the action of the cam portion 255 (Figs. 12 and 18) of the arm 254 against the collar 76 permits the arm 254 to swing in a clockwise direction out of the path of the rocket, which is then free to be ejected from the magazine through the collar 76 and along a pair

of parallel rails 386 fixed to the collar, by a blast of air passing through the projection tube 80.

Operation

- 5 The manner in which the several mechanisms operate has already been fully explained. It will suffice, therefore, to summarize briefly the operation of the apparatus.
- 10 It will be assumed that the magazine, fully loaded with rockets, has been installed in the bomb bay of an airplane and adjusted in the desired angular position in the manner explained above. Referring to Fig. 5, which shows the parts in their inoperative positions, the cam roller 232 carried by the clutch shifting lever 166 is in engagement with a notch 230 in the cam 226, the latch 216 is in engagement with a depression in the cam 228, the brake shoe 182 is in engagement with the brake disk 180, and the clutch 164 is disengaged. To operate the apparatus the pilot first closes the motor switch and the solenoid switch. The pilot next closes the indexing switch, whereupon the indexing solenoid 204 is energized and, through the clutch tripping lever 196, latch lever 212 and latch 216, actuates the clutch shifting lever 166 to swing in a counterclockwise direction to release the brake 182 from engagement with the brake disk 180 and to engage the clutch so as to bring the worm sleeve 151 into driving engagement with the drive shaft 152 to rotate the indexing shaft 122. Counterclockwise swinging movement of the lever 166 causes the cam roller 232 to be disengaged from the notch 230 in the cam 226, the roll thereafter riding in engagement with the periphery of the cam between two notches until it engages in the next notch in the cam, whereupon the lever 166 swings in the reverse direction to cause the clutch to be disengaged and the brake to be applied after the
- 15 25 lever 166 has swung in a clockwise direction to bring the cam roller 232 into engagement with the next notch in the cam 226. The roll thereafter riding in engagement with the periphery of the cam 226 causes the cam roller 232 to be disengaged from the notch 230 in the cam 226, the roll thereafter riding in engagement with the periphery of the cam between two notches until it engages in the next notch in the cam, whereupon the lever 166 swings in the reverse direction to cause the clutch to be disengaged and the brake to be applied after the
- 20 30 lever 166 has swung in a clockwise direction to bring the cam roller 232 into engagement with the next notch in the cam 226. The roll thereafter riding in engagement with the periphery of the cam 226 causes the cam roller 232 to be disengaged from the notch 230 in the cam 226, the roll thereafter riding in engagement with the periphery of the cam between two notches until it engages in the next notch in the cam, whereupon the lever 166 swings in the reverse direction to cause the clutch to be disengaged and the brake to be applied after the
- 25 35 lever 166 has swung in a clockwise direction to bring the cam roller 232 into engagement with the next notch in the cam 226. The roll thereafter riding in engagement with the periphery of the cam 226 causes the cam roller 232 to be disengaged from the notch 230 in the cam 226, the roll thereafter riding in engagement with the periphery of the cam between two notches until it engages in the next notch in the cam, whereupon the lever 166 swings in the reverse direction to cause the clutch to be disengaged and the brake to be applied after the
- 30 35 lever 166 has swung in a clockwise direction to bring the cam roller 232 into engagement with the next notch in the cam 226. The roll thereafter riding in engagement with the periphery of the cam 226 causes the cam roller 232 to be disengaged from the notch 230 in the cam 226, the roll thereafter riding in engagement with the periphery of the cam between two notches until it engages in the next notch in the cam, whereupon the lever 166 swings in the reverse direction to cause the clutch to be disengaged and the brake to be applied after the
- 35 40 lever 166 has swung in a clockwise direction to bring the cam roller 232 into engagement with the next notch in the cam 226. The roll thereafter riding in engagement with the periphery of the cam 226 causes the cam roller 232 to be disengaged from the notch 230 in the cam 226, the roll thereafter riding in engagement with the periphery of the cam between two notches until it engages in the next notch in the cam, whereupon the lever 166 swings in the reverse direction to cause the clutch to be disengaged and the brake to be applied after the
- 40 45 chain of rocket carrying tubes has been moved through a distance equal to the spacing between the centers of two adjacent tubes.
- 45 The time required for moving one rocket carrying tube into rocket launching position is very brief, and the pilot may almost immediately operate the firing switch to fire the rocket located in the launching position. Upon operation of the firing switch, the firing solenoid 270 will be energized and, through the link 280, actuate the lever 284 to swing in a clockwise direction, as seen in Fig. 13, to cause the latch 322 to release the contact fingers 312 and, through the latch 290, to move the rack slide 298 upward, thereby causing the block 308 to rotate in a clockwise direction to bring the fingers 312 into engagement with the contact members on the rear end of the rocket to set off the igniter in the rocket, which in turn ignites the propelling charge. Should the firing switch be operated before a rocket is in correct
- 50 55 60 65 70 75 80 85 90 95 100 launching position, that is, before the indexing mechanism has come to a complete stop, the firing mechanism will be prevented from being operated by the engagement of the periphery of the cam 226 (Fig. 5) with the microswitch 376 which, as previously explained, is connected in the circuit controlling the firing mechanism. In other words, the firing mechanism cannot be operated unless this microswitch is in register with a notch 230 in the cam 226. At the same time, while a rocket is in launching position, engagement of the rocket flange with the retaining lever 240 will open the microswitch 268 which is connected in the circuit controlling the indexing mechanism, so that the indexing mechanism will be prevented from being operated by operation of

the indexing switch until the rocket has either been launched through the projection tube 80 or, in the case of a misfired rocket, has been ejected through the collar 76. In the event of a rocket being misfired or defective, the pilot may cause the rocket to be released by operating the release switch, which will energize the release solenoid 382 and actuate the retaining lever 240 to cause it to release the rocket so that it may be free to be ejected from the magazine by a blast of air passing through the projection tube.

Having described my invention, what I claim as new and desire to secure by Letters Patent of the United States is:

1. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, and remotely controlled firing means located on said magazine and operated independently of said indexing means to fire the rockets successively at the will of the operator.

2. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, and remotely controlled means on said magazine for firing each rocket after the same has been moved into said launching position, and manual locking means for rendering the firing means inoperative at will.

3. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means on said magazine for firing each rocket after the same has been moved into said launching position, retaining means located on said magazine and adapted to engage the rear end of a rocket in the launching position and to retain the rocket until fired by said firing means, and means associated with said retaining means and actuated by the blast of the fired rocket to cause said retaining means to release the rocket.

4. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means located on said magazine and actuated independently of said indexing means to fire the rockets successively, an electrical circuit controlling said firing means, switch means for closing said circuit, a normally closed switch in said circuit adapted to be opened by said indexing means during operation thereof, to break said circuit, thereby rendering the operation of said switch means

ineffective to operate the firing means before the completion of an indexing cycle.

5. An apparatus for launching rockets, having in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means on said magazine for firing each rocket after the same has been moved into said launching position, and means normally actuated by the successive rockets in the launching position to prevent operation of said indexing means while a rocket is in said launching position.

6. An apparatus for launching rockets, having in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means on said magazine for firing each rocket after the same has been moved into said launching position, retaining means located on said magazine and adapted to engage a rocket which has been moved into launching position and to retain it until fired by said firing means, means associated with said retaining means and actuated upon the firing of the rocket to cause said retaining means to release the rocket to permit it to be launched through said projection tube, and remotely controlled means for causing said retaining means to release an undischarged rocket to permit the same to be ejected from said magazine in a direction away from said projection tube by a blast of air passing therethrough.

7. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means on said magazine for firing each rocket after the same has been moved into said launching position, means associated with said indexing means and acting automatically to prevent actuation of said firing means during operation of said indexing means, and means normally actuated by the successive rockets in the launching position to prevent operation of said indexing means while a rocket is in said launching position.

8. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means on said magazine for firing each rocket after the same has been moved into said launching position, manually operated means for locking the firing means to prevent operation thereof when the apparatus is not in use, retaining means located on said magazine in position to engage a rocket which has been moved into launching

position and to retain it until fired by said firing means, means actuated upon the firing of the rocket to cause said retaining means to release the rocket, means associated with said indexing means and acting automatically to prevent actuation of said firing means during operation of said indexing means, means normally actuated by a rocket in the launching position to prevent operation of said indexing means while a rocket is in said launching position, and remotely controlled means for causing said retaining means to release an undischarged rocket to permit the same to be ejected from said magazine by a blast of air passing through said projection tube.

9. The combination of an airplane and an apparatus for launching rockets therefrom, comprising a projection tube mounted outside the airplane, a magazine for holding a plurality of rockets, said magazine being mounted within the airplane but projecting therethrough and being connected to said projection tube, remotely controlled indexing means on said magazine for moving said rockets successively into launching position in register with said projection tube, and remotely controlled firing means on said magazine actuated independently of said indexing means to fire said rockets successively through said projection tube at will after the rockets have been moved into said launching position.

10. The combination of an airplane and an apparatus for launching rockets therefrom, comprising a projection tube mounted outside the airplane, a magazine mounted within the airplane but projecting therethrough and connected to said projection tube, a plurality of rocket carrying tubes in said magazine connected together to form an endless chain, indexing means on said magazine controlled by the airplane pilot for rotating said rocket carrying tube chain to move said tubes successively into rocket launching position in register with said projection tube, and means on said magazine under the control of the pilot for successively firing said rockets at will after the same have been moved into said launching position.

11. The combination of an airplane and an apparatus for launching rockets therefrom, comprising a projection tube mounted outside the airplane, a magazine mounted within the airplane but projecting therethrough and connected to said projection tube, a plurality of rocket carrying tubes in said magazine connected together to form an endless chain, means in said magazine for guiding said rocket carrying tube chain in a closed, non-circular path, indexing means on said magazine controlled by the airplane pilot for rotating said rocket carrying tube chain to move said tubes successively into rocket launching position in register with said projection tube, and means on said magazine under the control of the pilot for successively firing said rockets at will after the same have been moved into said launching position.

12. The combination of an airplane and an apparatus for launching rockets therefrom, comprising a projection tube mounted outside the airplane, a magazine mounted within the airplane but projecting therethrough and connected to said projection tube, a plurality of rocket carrying tubes in said magazine connected together to form an endless chain, means in said magazine for guiding said rocket carrying tube chain in a closed, non-circular path, a driven shaft on said magazine, means on said shaft for supporting and moving successive rocket carrying tubes

into said rocket launching position, remotely controlled power-operated means mounted on said magazine for driving said shaft to cause said rocket carrying tube chain to be rotated, starting and stopping means associated with said driving means and acting automatically to stop rotation of said shaft after said rocket carrying tube chain has been rotated a distance sufficient to move one rocket carrying tube into rocket launching position, and means under the control of the pilot for firing a rocket at will after the same has been moved into said launching position.

13. The combination of an airplane and an apparatus for launching rockets therefrom comprising a projection tube mounted outside the airplane, a magazine mounted within the airplane but projecting therethrough and connected to said projection tube, a plurality of rocket carrying tubes in said magazine connected together to form an endless chain, means in said magazine for guiding said rocket carrying tube chain in a closed, non-circular path, a driven shaft on said magazine, means on said shaft for supporting and moving successive rocket carrying tubes into said rocket launching position, remotely controlled power-operated means mounted on said magazine for driving said shaft to cause said rocket carrying tube chain to be rotated, auxiliary manual means for driving said shaft, starting and stopping means associated with said driving means and acting at predetermined times in the power or manual operation of said driving means automatically to stop rotation of said shaft after said rocket carrying tube chain has been rotated a distance sufficient to move one rocket carrying tube into rocket launching position, and means under the control of the pilot for firing a rocket at will after the same has been moved into said launching position.

14. The combination of an airplane and an apparatus for launching rockets therefrom, comprising a projection tube pivotally mounted outside the airplane, a magazine removably mounted within the airplane but projecting therethrough and connected to said tube, means for adjusting said magazine and tube as a unit relatively to the airplane, means on said magazine for moving said rockets successively into a launching position in register with said projection tube, and means for firing each rocket after the same has been moved into said launching position.

15. An apparatus for launching rockets, having, in combination, a magazine for a plurality of rockets, power-operated indexing means for feeding said rockets successively to a position from which they can be fired, a cam associated with said indexing means and acting to cause the operation of said indexing means to stop at predetermined intervals during the feeding movement of said rockets, remotely controlled firing means actuated independently of said indexing means to fire the rockets successively at the will of the operator and means actuated by said cam to prevent actuation of said firing means during operation of said indexing means to feed a rocket to said firing position.

16. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively

into a launching position in register with said projection tube, remotely controlled means on said magazine actuated at will and independently of said indexing means to fire a rocket after the same has been moved into said launching position, said firing means comprising a pair of contact members arranged to engage each rocket, resilient means associated with said contact members for permitting said members to yield independently of each other upon engagement with a rocket, and means arranged to energize said members just before their engagement with a rocket to cause them to ignite the charge in the rocket.

17. An apparatus for launching rockets, having, in combination with a projection tube through which said rockets are to be launched, a magazine connected at one end thereof to said projection tube and adapted to hold a plurality of rockets, remotely controlled indexing means on said magazine for moving the rockets successively into a launching position in register with said projection tube, remotely controlled means on said magazine for firing each rocket after the same has been moved into said launching position, said firing means comprising a pair of contact members yieldable independently of each other, a spring-actuated latch normally holding said contact members in inoperative position, and means for actuating said latch to cause it to release said contact members upon actuation of said firing means by the operator to cause them to fire a rocket, said latch being actuated in timed relation to the movement of said contact members to be returned into a position to again engage the contact members upon their return to inoperative position.

18. An apparatus for launching rockets, having, in combination with a projection tube through which said rockets are to be launched,

a magazine connected at one end thereof to said projection tube and adapted to hold a plurality of rockets, remotely controlled indexing means on said magazine for moving the rockets successively into a launching position in register with said projection tube, and operator controlled contact members arranged to engage a rocket in launching position and to fire the same, a spring actuated latch normally holding said contact members in inoperative position, means for actuating said latch to cause it to release said contact members, and a locking plunger which in one position thereof is arranged to prevent said latch actuating means from operating to release said latch.

LESTER S. MACDONALD.
